CUTTING DIE

George Donaldson and John Paul Klee, Leicester, England, assignors to United Shoe Machinery Corporation, Flemington, N. J., a corporation of New Jersey

Application September 22, 1942, Serial No. 459,272
In Great Britain November 3, 1941

2 Claims. (Cl. 164—29)

This invention relates to dies and is herein illustrated as embodied in a cutting die of the type disclosed in United States Letters Patent No. 1,124,739, granted January 12, 1915, upon application of John J. Heys.

In cutting sole blanks from sheet material, such as leather, use is commonly made of presses in which are employed dies, of the type referred to, which are moved manually from one operative position to another on a piece of sheet material located upon a cutting bed. Such dies are usually provided with guards to prevent the operator's fingers from accidentally assuming a dangerous position between the upper portion of the die and the presser member which performs the cutting operation.

It is an object of the present invention to provide an improved die including a guard member of novel construction, such that it can be quickly and conveniently attached to dies of various shapes and sizes. To this end and as illustrated, the invention comprises a die having an upstanding side wall and a guard member secured to the wall, the guard member being in the form of a strip of flexible material, such as rubber, reinforced by metal. Preferably the strip has an outwardly extending flange which is notched to facilitate the bending of the strip to conform to the shape of the die. An advantage of this construction is that the guard member can be quickly bent to conform to the wall of a die of any shape and can be readily secured in fixed position.

These and other features of the invention are illustrated in the following specification and in the accompanying drawing and are pointed out in the claims.

In the drawing,

Fig. 1 is a perspective view of a die embodying the invention; and

Fig. 2 is a vertical cross-sectional view through a side wall of the die taken along line II—II of Fig. 1.

The die shown in Fig. 1 is a hollow die having an upstanding side wall 10 provided with a pressure-receiving edge 11 and a cutting edge 12, there being adjacent to the upper edge a plurality of guard members 14 and 16. The die shown is one which is suitable for cutting blanks for half-soles, and has a forepart portion 17 and a waist portion 18 having corners 20.

Each of the guard members 14 and 16 is composed of a strip of molded rubber, channel-shaped in cross section, and having a vertical flange 22 and an outwardly extending flange portion 24 which is notched to form a plurality of tabs 26. Inserted in each strip is a metal reinforcing member or band 28 which is sufficiently soft so that it can be bent with the strip to conform to the shape of the side wall of the die, but will retain substantially the shape into which it is bent. The

notched construction of the flange 24 permits the bending of the strips about the side wall of the die even at the corners, without bunching of the material. The metal reinforcing member serves to maintain the strips in position closely in contact with the wall of the die, the strips being rigidly secured thereto by rivets 30.

In order to facilitate handling of the die, there are provided finger grips 32 in the form of rubber washers having concave head portions 34, the washers being secured to the side wall of the die by screws 36. These grips are so positioned along the sides of the die that a hand of the operator, when it grasps an end of the die, can readily be positioned with a finger and the thumb on the opposite sides of the die in engagement with two of the grips. This construction tends to prevent dies, which are often of considerable weight, from slipping out of the operator's hands.

20 In locating the die upon material in a press, the operator will usually pick up the die with both hands, with the middle fingers and thumbs in engagement with the grips 32 and with the hands positioned below the guard members 14 and 16. The tabs 26 will prevent any portion of the operator's hands from extending beyond the upper edge of the die in the position in which it might be crushed between the presser member and the die.

25 Having thus described our invention, what we claim as new and desire to secure by Letters Patent of the United States is:

1. In a hollow cutting die having a wall provided with a cutting edge and a pressure receiving edge, a strip of flexible material bent along the pressure receiving edge, the strip comprising a portion engaging the wall and a notched flange extending outwardly from the wall to form a guard member, a metal reinforcing strip embedded in and approximately the length of that portion of the flexible strip which engages the wall of the die for maintaining said flexible strip in position on and for conforming it to the contour of said wall, and means to fasten said strips to said wall.

2. In a hollow cutting die having a wall provided with a cutting edge and a pressure-receiving edge, a strip of flexible material bent along the pressure-receiving edge, the strip comprising a portion engaging the wall and a flange portion extending outwardly from the wall to form a guard member, a metal reinforcing member embedded in said portion of the strip engaging the wall, said member extending along the wall substantially throughout the length of the flexible strip for maintaining the strip in position on and to conform it to said wall, and means to secure said strip and member to said wall.

GEORGE DONALDSON.
JOHN PAUL KLEE.
